UNITED STATES PATENT OFFICE.

ISIDORE H. WEINER, OF HOUSTON, TEXAS.

REPORTER'S DESK.

SPECIFICATION forming part of Letters Patent No. 348,706, dated September 7, 1886.

Application filed February 11, 1886. Serial No. 191,596. (No model.)

To all whom it may concern:

Be it known that I, ISIDORE H. WEINER, a citizen of the United States, residing at Houston, in the county of Harris and State of Texas, have invented certain new and useful Improvements in Reporters' Desks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention is a portable desk intended especially for the use of reporters, stenographers, and students; and it consists in the novel features shown in the accompanying drawings, and hereinafter described and claimed.

In the drawings referred to, Figure 1 is a perspective view showing the desk in position for use, and Fig. 2 is a perspective view showing it folded for transportation.

In the following description I designate that part of the desk which in operation is nearest the writer, the front, and the opposite side the back of the desk.

My desk consists, essentially, of a base, A, a top, B, and intermediate connection composed of sections C D E. The top B is pivotally connected with the section C by brackets *a*, which are rigidly secured to the top B and pivoted to the section C, as will be understood on reference to the drawings. Brackets *b*, similar to the brackets *a*, connect the sections C and D. They are pivoted to the section C and rigidly secured to the section D, as shown. The sections D and E are hinged together by hinges *c*, secured to the back thereof, and a hook, F, pivoted upon the front of the section D near its lower edge, engages a pin, G, on the section E near its upper edge, in order to give rigidity to the device. Upon the front of the section D, I place along the side edges and the lower edge the strips *d e f*, and stretch cords *g* across the said section D by securing their ends to the strips *d e* in any suitable manner. I thus provide a pocket or receptacle for papers, notebooks, &c. The strip *f* along the lower edge of the section D is cut away at its center, so as to provide for the proper working of the pivoted hook F. It will be understood that instead

of being entirely cut away, as shown in the drawings, this strip *f* could be mortised on the side next the strip *d* or *e*, and the hook F passed through the mortise. The section E is connected with the base A by brackets *h*, similar to the brackets *a* and *b*, pivoted to the said section and rigidly secured to the base.

As before mentioned, Fig. 1 shows the desk in position for use. The base is swung back 60 of the section E and placed on the ground or floor, the section E standing at an incline and the back thereof resting against the edge of the base. The sections D and E will be in the same line as the hinges *c*, and the hook F and pin G 65 will hold them in place, as will be readily understood. The lower edge of the upper section, C, will be in front of and below the upper edge of the section D, and the said section C will have an inclination backward, its back 70 resting on the upper edge of the section D. The top B will be extended out in front of the section C, as shown. The back edge of the top B is beveled so as to rest against the section C and have the proper inclination for easy writing. The angle which the section C forms 75 with the section D and that which the section E forms with the base may be varied by securing the brackets *b* and *h* nearer to or farther from the ends of the sections.

By having the several sections assume the relative inclinations shown and described the pressure exerted on the top in writing is transmitted downward to a point within the outline 85 of the base, and the device thereby prevented from tipping over.

When the device is to be folded for transportation, the several sections are swung around in the directions indicated by the arrows—*i. e.*, the top is swung around back of the section C; 90 the section C and the top are then folded down on the section D; the hook F is disengaged from the pin G; the base is swung around in front of the section E, and the whole folded together upon the hinges *c*, when the device will 95 appear as shown in Fig. 2. In order that the sections may not bind when swinging past each other, I form them with rounded end edges, as shown.

The advantage of my desk will be readily 100 appreciated. When the reporter wishes to take notes, he sets up the desk, and instead of

holding his note book in his hand places it on the desk, and is then enabled to write more conveniently and rapidly. The desk is not only peculiarly adapted to reporter's use, but can 5 also be used to advantage in offices, warehouses, &c.

Heretofore desks have been made in which the top and base have been connected by intermediate hinged connections, so as to permit 10 the folding of the top close to the base and its elevating or unfolding therefrom, said intermediate hinged connections being sustained by independent braces. By my construction the use 15 of independent means or braces to sustain the top in its elevated or unfolded position is obviated, as the sections are flexibly connected by braces forming a hinge-joint in such manner that they are self-sustaining when unfolded.

Having thus described my invention, what 20 I claim, and desire to secure by Letters Patent, is—

1. A portable folding desk comprising the following elements in combination: a top and base arranged at a distance apart the one 25 above the other, an intermediate connection inclining from a vertical line, having a portion of the front side, near the upper end, in contact with the rear edge of the top, forming a rest or stop for said top, and a portion of the rear side, 30 near the opposite end, in contact with the front edge of the base, which latter forms a rest or stop for the lower end of the section, and brack-

ets, as *a* and *h*, connecting the top and base with the upper and lower portions of said intermediate connection, respectively, by a hinge-joint, forming a self-sustaining structure when the device is unfolded, substantially as shown and described. 35

2. As an improved article of manufacture, the herein shown and described portable folding desk, consisting of the base *A*, sections *D* and *E*, hinged together, hook *F* and pin *G*, for rigidly bracing the hinged joint between them, braces *h*, pivotally connecting the lower end of section *E* with the base, and having its side 45 abutting against the end of the base to form a stop, section *C*, having its side abutting against the end of section *D*, brackets *b*, pivotally connecting the meeting ends of the sections *C* and *D*, top *B*, having its end resting against the 50 side of the section *C*, and brackets *b*, pivotally connecting the sections *B* and *C*, the parts being disposed whereby the top and sections may be folded close upon the base, and when unfolded will mutually brace each other and form 55 a self-sustaining structure, substantially as shown.

In testimony whereof I affix my signature in presence of two witnesses.

I. H. WEINER.
